UNITED STATES PATENT OFFICE.

GEORGE EASTERBEE, OF PORTLAND, OREGON.

COIN-CONTROLLED MECHANISM FOR DISPENSING NEWSPAPERS.

SPECIFICATION forming part of Letters Patent No. 659,140, dated October 2, 1900.

Application filed June 8, 1899. Serial No. 719,843. (No model.)

To all whom it may concern:

Be it known that I, GEORGE EASTERBEE, a citizen of the United States of America, and a resident of Portland, in the county of Multnomah, State of Oregon, have invented a new and useful Coin-Controlled Mechanism for Dispensing Newspapers, of which the following is a specification, reference being had to the accompanying drawings as a part thereof.

10 The object of my invention is to obtain a coin-controlled mechanism whereby newspapers may be automatically dispensed—that is to say, my invention comprises a platform designed to carry a stock of newspapers so as 15 to bring the uppermost paper in contact with an expelling device, such platform being suspended by mechanism adapted to gradually raise the same as the papers are withdrawn to bring the papers in contact with the expelling device successively, and a motor for 20 operating the various devices, which motor is normally stopped, but released by depositing a coin on the end of a lever-arm, so that by depositing such coin in the slot therefor 25 provided in the case the motor may be set in operation and the machine will deliver one of the newspapers within it stored.

In the drawings, Figure 1 is an elevation of my invention, the side of the casing being 30 removed, so as to show the mechanical devices used by me for carrying my invention into effect. Fig. 2 is a front elevation of my machine inclosed in its casing, part of which casing is broken away, so as to afford a front 35 view of the devices shown in Fig. 1. Fig. 3 is a plan of the motor whereby the devices of my machine are set into operation. Fig. 4 is a detail of the lever-arm on the extremity of which the coin whereby the mechanism is to 40 be set into operation is deposited, and this figure also shows the certain parts of my invention immediately coöperating with said lever. Fig. 5 is a partial end elevation of the same devices shown in Fig. 4. Fig. 6 is 45 a plan of the same devices seen in Figs. 4 and 5. Fig. 7 is a detail of a swinging shelf upon which the coin that has been deposited on the end of the said lever and has caused the machine to operate is dropped and where 50 the nickle remains in view of the operator until a second coin has been used in operating the machine, as will be more fully ex-

plained. Fig. 8 is a perspective elevation of the same devices shown in Fig. 7, and Fig. 9 is a detail showing the end of the friction-drum whereby the uppermost paper is expelled and the pulleys on the shaft of and communicating motion to such drum. 55

The letters designate the parts referred to in the description of my invention. 60

My invention also comprises certain other mechanical devices which are used in co-operation with the devices already mentioned, all of the same being illustrated in the drawings above referred to. 65

a represents a casing in which the mechanism of my device is inclosed.

b is a platform having four standards *b'*, supporting such platform on the floor of the case. 70

c is a spring-controlled motor secured to the floor of the casing and comprising a pair of gears *c'* *c*². The gear *c'* is loose on its axle *c*³. Such axle carries a fast ratchet-wheel *c*⁴, engaged by a pawl on the said gear *c'*, and a spring (not shown in the drawings) imparts motion to the larger gear-wheel in the usual way. The spring is wound up by means of a key placed on the squared end of the shaft *c*³. 75

The larger gear meshing with the smaller gear *c*² drives that and therewith a drum *d*, affixed to the axle of the gear *c*². On the drum *d* is wound a cord *e*, passing over a pulley *f* and ascending to and rounding a pulley *i*, thence descending and passing around in one 85 of the grooves of pulley *h*, thence again ascending and passing around in one of the grooves of pulley *g*, thence again descending and making a second turn around pulley *h*, thence again ascending and making a second 90 turn around pulley *g*, and finally descending to and being fastened to the bearings *b*² for the pulley *h*, affixed to the platform *b*. A like cord *e'*, also winding on the drum *d*, but from an opposite direction, travels to the left over 95 a pulley *f'* and around pulleys *g'* *h'* *i'* and is finally connected to the bearings *b*³ for the pulley *h'*, affixed to the platform *b* in the same manner as has been described of the cord *e*. The axle *k*' of the drum *k* is provided at its left 100 end with a gear-wheel *l*, meshing below with a smaller gear-wheel *m*, journaled on a short axle *m'*, affixed to the wall of the case. The hub *m*² of the gear-wheel *m* has a shoulder

cut in it, which interlocks with a like shoulder in a sleeve n . With such sleeve are connected a link n' and the lever n^2 , fulcrumed on an axle n^3 , supported in boxes n^4 n^5 , af-
5 fixed to the partition-wall o . p is a lever-arm pivotally supported from such wall o and pro-
vided with a slotted link p' , engaging the end
10 of the lever n^2 , such lever p having further
a counterweight p^2 and a knee p^3 for receiv-
ing the coin. This lever-arm and co-operat-
ing mechanism must be neatly adjusted. It
15 is intended to operate as follows: Upon plac-
ing the coin in the knee p^3 of the lever p the
weight of such coin will cause the lever to
descend, drawing down the slotted link p' and
therewith the lever n^2 , moving the sleeve n
20 to the right, and thereby disengaging the hub
of the smaller wheel m and allowing the lat-
ter to run as an idler. The control of the
larger gear l being thus removed, the moment
25 such disengagement takes place the gear l will
make a partial revolution, being actuated by
the cords e e' , winding up on the revolving
drum d , responding to the spring-controlled
30 motor. The coin having fallen off the end of
the lever-arm p allows the counterweight
 p^2 to right the same, again lifting the lever
 n^2 and moving the sleeve n back toward its
35 normal position and ready to engage the hub
of the gear m as soon as that returns to its
normal position. The gears l and m are so
proportioned that a quarter-revolution of the
first-named gear will allow a complete rev-
olution of the last-named gear. The drum k
40 is of the same size as the gear l and makes a
quarter-revolution too. The peripheral sur-
face of such drum is faced with some friction
material, like rubber, which coming in con-
tact with the uppermost newspaper expels
45 such paper down the chute q and out of the
machine. The cords e e' and the series of
pulleys over which such cords are led are such
as to lift the platform b about one-quarter of
an inch with each operation of the machine,
50 so that as the uppermost paper is expelled
the next upper paper is again brought in po-
sition to be expelled upon the second opera-
tion of the machine, and so on.

As the thickness of papers varies, it is ad-
55 visable that the pulleys i i' comprise each a
stepped series of pulleys, so that the cords
 e e' may be shifted from one to the other of
the grooves on the pulleys i i' , as may be re-
quired, for adjusting the speed of the lift of
55 the platform and that by such means the lift
of the platform may be regulated and con-
formed to the thickness of the newspapers.
A slot r is provided in the upper part of the
60 case in which to insert the coin, such slot
opening into a chute r' , delivering the coin
on the said knee p^3 of the lever p .

For the purpose of retaining the coin used
for the purpose of operating the machine, in
view to enable a bystander to see that the
65 machine is not imposed upon, I have con-
trived the device more particularly illus-
trated in Figs. 7 and 8. The same consists of

two swinging shelves s s' , supported on the
axles t t' and connected at their right ends
by arms u u' , and they are intended to oper-
ate as follows: When first starting the
70 machine, a coin should be placed on the lower
shelf s' . The front of the case at this part
is provided with a glass, so that such coin
may be plainly seen. When a second coin is
75 now inserted in the machine for operating
the same and expelling a newspaper, such
second coin will be dropped on the upper
shelf s . The two shelves s s' are, however,
80 so balanced that they will hold but one coin.
Therefore upon the second coin being dropped
on the upper shelf the counterbalancing
weight of the arms u u' will be overcome and
85 the two shelves tipped, allowing the lower
coin to drop to the bottom of the machine in
some box therefor provided, and the moment
the lower shelf is thus released of its weight
the weight of the arms u u' will again right
90 the shelves s s' to their normal position,
catching the coin dropped on the upper shelf
as it falls therefrom on the lower shelf.

Having fully described my invention, now
what I claim, and desire to secure by Letters
Patent, is—

1. In a machine for the purpose specified, 95
the combination of a lifting-platform, a fric-
tion-drum journaled horizontally above the
lifting-platform, for expelling the papers, a
mechanical power for operating the said lift-
ing-platform and said friction-drum con-
100 jointly and relatively, and a clutching device
adapted to normally resist the action of the
operative power, said clutching device hav-
ing a portion depressible by a coin or weight,
the depression of which portion releases the 105
resistance of said clutching device and allows
said paper lifting and expelling devices to
operate; and said depressible portion being
adapted to automatically discharge said coin
110 or weight again to restore the clutching de-
vice to its operative state, substantially as
described.

2. In a machine for the purpose specified,
the combination of a lifting-platform, a fric-
tion-drum journaled horizontally above the 115
lifting-platform, for expelling the papers,
cords and pulleys, and an automatic device
for winding up said cords and lifting said plat-
form, there being also pulleys on the spindle
120 of the said drum over which said cords pass
and whereby the power applied for lifting the
platform is transmitted to said drum and
operates the same, and a clutching device
adapted to normally resist the action of said
125 wind-up device, said clutching device being
connected with a fulcrumed lever whereby
said clutching device is thrown into and out
of an operative state, and the free end of said
lever being adapted to hold a coin or weight,
while in an upright position, wherewith to 130
depress said lever and release the resistance
of such clutching device, substantially as de-
scribed.

3. A machine for the purpose specified,

comprising a case, a lifting-platform, a friction-drum for expelling the papers, cords and pulleys for lifting said platform and an automatic device for winding up said cords, 5 pulleys on the spindle of the said friction-drum, over which pulleys said cords pass and whereby the power applied for lifting the platform is transmitted to said drum and operates the same; means for relatively controlling the lift of the said lifting-platform; 10 a gear on the spindle of the friction-drum; a smaller gear meshing therewith, loosely mounted on a short spindle affixed to a wall of the casing; a clutch engaging such smaller 15 gear, and a fulcrumed lever and coöperating device whereby said clutch may be thrown in and out of contact with said smaller gear, the said lever and said coöperative device being adapted to normally keep the said clutch in 20 engagement with said smaller gear, and the upper end of said lever being adapted, while in a raised position, to hold a coin or weight

whereby to depress said lever and release the resistance of said clutching mechanism, an opening in the case for receiving such coin or 25 weight, a chute from such opening leading to the receiving end of the lever, and a trap for catching the coin or weight as it falls from the end of the lever; said trap being adapted to hold the coin or weight that has been deposited in the machine for operating the same, and discharging said coin in a receptacle therefor provided upon a second coin being introduced into the machine, and there being a glass in the front of the machine affording a view of the operation of said trap, 30 substantially as described.

In testimony whereof I have hereunto affixed my signature in the presence of two witnesses.

GEORGE EASTERBEE.
